GROUNDING DEVICE

Ford Pennell, Webster Groves, Mo.

Application September 28, 1940, Serial No. 358,789

5 Claims. (Cl. 174—6)

The invention relates to the grounding of telephone, telegraph, electric lighting and other electric wires strung on poles and consists in a simple, effective grounding member which may be associated with the pole.

One object of the invention is to reduce the expense of grounding the wires carried by the pole by providing an inexpensive device which may be installed along with the pole and thereby avoiding digging or otherwise forming an additional opening in the ground for a grounding device.

Another object of the invention is to insure that the grounding device will be under pressure contact with the ground and, preferably, at such depth that it will always be in moist earth, without depending upon the operator properly imbedding the grounding device, as is required where the latter is imbedded in the earth separately from the pole.

Another object is to form a grounding device which is light in weight and which may be readily stacked one on top the other in a storeroom or in shipping and thereby reduce storage and transportation expense and difficulties in handling.

These objects are attained by the structure illustrated in the accompanying drawing, in which—

Figure 1 is an elevation of a pole set in a suitable hole in the earth and equipped with the present invention.

Figure 2 is a plan view of one form of grounding plate of substantially flat section arranged for application to the bottom of the pole, as indicated in Figure 1.

Figure 3 is a similar view of another form of grounding plate corrugated for a purpose referred to below.

Figure 4 is a transverse section taken on the section line 4—4 of Figure 3.

Figure 5 is a similar view of another form of corrugated plate.

Figure 6 is a transverse section taken on the corresponding section line 6—6 of Figure 5.

Figure 7 is a plan view of a skeletonized grounding plate.

Figure 8 is a transverse section taken on the section line 8—8 of Figure 7.

In Figure 2, the grounding device is merely a flat plate 1, preferably of copper or other readily conductive material, preferably provided with openings 2 whereby the plate may be nailed or screwed into the pole P, as indicated at 3 in Figure 1. The plate has brazed, or otherwise

secured thereto, a lug 4 with an opening 5 for receiving a grounding wire, as indicated at 6 in Figure 1. A screw 7 threaded into one side of lug 4 serves to clamp the rod to the lug. The upper end of wire 6 may be connected to the wires to be grounded in the usual manner.

The plate 10 shown in Figures 3 and 4 is provided with a circular corrugation 11 and transverse corrugation 12 to serve to reinforce the plate while it is being handled and applied to the pole, and corrugation 12 also provides a recess for receiving and forming an extended bearing for the end portion of the grounding wire 13.

The plate is perforated as indicated to receive attaching nails or screws and to provide for the drainage of water through the plate.

The plate 20, shown in Figures 5 and 6, is provided with a series of parallel, deep, chordal corrugations 21 extending from edge to edge of the plate and substantially increasing its surface area. One of these corrugations may receive the end portion of the grounding wire 22 and the upper portions of the corrugations may be perforated, as indicated at 23, to receive nails, screws, or other attaching elements.

The grounding device shown in Figures 7 and 8 consists of an elongated member 30 forming an annulus 31 corresponding to the circumference of the pole to which it is to be applied, and also portions bent back and forth forming chordal elements 32. The device may be formed of a flat strip or, as shown, it may consist of an end portion of a grounding wire 33 bent to the desired figure and preferably then pressed into the flat section shown. Either construction increases area in contact with the ground and provides substantial rigidity for the device in packing and handling. Preferably, the elongated member has portions bent or looped one around the other, as indicated at 34, to rigidify the member and maintain the assembly of the meeting parts.

In each form of the invention, the device may be applied readily to the bottom of the pole, and when the pole is inserted in the hole in the ground the device will be thrust into contact with the ground by the weight of the pole and there will be additional contact area provided by the grounding wire extending upwardly alongside of the pole. The necessity of providing a substantially deep hole for holding the pole erect will insure the grounding device being placed at a suitable depth so that the moisture in the earth will contribute to the efficiency of the grounding. As pointed out above, it will be unnecessary to provide a rigid rod which can be driven into the earth

or to make a separate excavation for burying a grounding plate or wire. The device is simple, economical and effective for its intended purpose.

The essential features of the device may be embodied in various arrangements other than those shown in the drawing, and the exclusive use of such modifications of the structure as come within the scope of the claims is contemplated.

What is claimed is:

1. As a new article of manufacture, a grounding device unit of the class described applicable in the field to the bottom end of a transmission line pole and comprising a flat member of metal having a high degree of conductivity of electric currents and corresponding in diameter to the diameter of a pole to which it is to be applied so that the member may be inserted with the pole into a deep, relatively small diameter hole in the earth and be pressed by the weight of the pole into contact with the earth at the bottom of the hole, there being a grounding line secured to said member to extend upwardly therefrom for connection above ground to a wire carried by the pole, the member being corrugated transversely of its thickness to stiffen the member during shipping, storing and installation and to increase its surface area without extending the member beyond the sides of the pole.
2. A grounding device as described in claim 1 in which the grounding line has an end portion secured in one of the member corrugations and projecting outwardly and upwardly from the edge of the member.
3. A grounding device as described in claim 1 in which one of the corrugations is an annular corrugation adjacent the periphery of the member and another of the corrugations is disposed diametrically and the lower end of the grounding line is secured in one of the corrugations.
4. As a new article of manufacture, a ground-

ing device unit of the class described applicable in the field to the bottom end of a transmission line pole and comprising a flat member of metal having a high degree of conductivity of electric currents and corresponding in diameter to the diameter of a pole to which it is to be applied so that the member may be inserted with the pole into a deep, relatively small diameter hole in the earth and be pressed by the weight of the pole into contact with the earth at the bottom of the hole, the member being corrugated transversely of its thickness, to stiffen the member during shipping, storing and installation and to increase its surface area without extending the member beyond the sides of the pole, the unit including structure facilitating assembly with the member of an end portion of a grounding line so as to assure substantial electrical contact between them.

5. As a new article of manufacture, a grounding device unit of the class described applicable in the field to the bottom end of a transmission line pole and comprising a flat member of relatively thin metal having a high degree of conductivity of electric currents and corresponding in diameter to the diameter of a pole to which it is to be applied so that the member may be inserted with the pole into a deep, relatively small diameter hole in the earth and be pressed by the weight of the pole into contact with the earth at the bottom of the hole, the member being reinforced transversely of its thickness, to stiffen the member during shipping, storing and installation and to increase its surface area without extending the member beyond the sides of the pole, the unit including structure facilitating assembly with the member of an end portion of a grounding line so as to assure substantial electrical contact between them.
